Primary Examiner — Ian Simmons*Assistant Examiner* — Dana L Meyrow(74) *Attorney, Agent, or Firm* — Fulbright & Jaworski LLP(57) **CLAIM**

The ornamental design for a cosmetic container, as shown and described.

DESCRIPTION

FIG. 1 is a top perspective view of a cosmetic container showing my new design;

FIG. 2 is a side elevation view thereof, all other sides being identical; and,

FIG. 3 is a top plan view thereof.

The dashed lines in FIGS. 1 and 2 represent environment structure and form no part of the claimed design. All other surface(s) or portion(s) of my design not shown in the figures or otherwise described in the specification form no part of the claimed design.
